UNITED STATES PATENT OFFICE.

WILLIAM E. D. STOKES, JR., OF NEW YORK, N. Y., AND GEORGE W. DAVIS, OF GALILEE, NEW JERSEY, ASSIGNORS TO WILLIAM E. D. STOKES, OF NEW YORK, N. Y.

SPARK-GAP-COOLING DEVICE.

1,073,371.

Specification of Letters Patent. Patented Sept. 16, 1913.

Application filed October 9, 1908. Serial No. 457,010.

To all whom it may concern:

Be it known that we, WILLIAM E. D. STOKES, Jr., and GEORGE W. DAVIS, citizens of the United States, residing at New York, in the county of New York and State of New York, and at Galilee, in the county of Monmouth and State of New Jersey, respectively, have invented a new and useful Improvement in Spark-Gap-Cooling Devices, 10 of which the following is a specification.

In wireless telegraph or telephone systems employing a spark gap, it has heretofore been proposed to cool the terminals, the space between which forms the gap, by an air blast or current directed at right angles or laterally to the gap. This has not proven efficient in practice, because if a blast is used strong enough to effect the proper cooling function, it is apt to blow out or extinguish 20 the spark or arc and cut down the oscillation period. To overcome this difficulty we have arranged the cooling device, such as an air blast nozzle, so as to direct the blast directly to one or both terminals substantially parallel with the action of the spark or arc. In this way the terminals can be kept cool and the tendency to blow out the spark or arc can be eliminated.

The invention is shown in the accompanying drawing in which,

In Figure 1 a sending or transmitting plant of a wireless telegraph station is shown in diagram with our improvement applied thereto; and Figs. 2 and 3 are a 35 plan and side elevation respectively of the cooler which is arranged between the terminals in Fig. 1.

Referring to the drawings and in detail, A designates the aerial of a wireless station, 40 which is connected to the secondary S of an induction coil I, which is provided with the usual spherical terminals T-T, and in which one terminal is connected to the aerial A, and the other to the ground or earth E. 45 P designates the primary of the induction coil which is in circuit with a source of current, as a generator D, and which circuit is provided with a telegraph key K, an interrupter or breaker B, and a condenser C. 50 These parts are arranged to represent an ordinary close-coupled transmitting plant.

In operation when the key is depressed a series of electrical impulses will be caused to flow through the primary P which will in-

duce high tension alternations in the secondary S, which will cause sparks between the terminals T-T, and will impress electrical oscillations on the aerial A. In use these terminals become heated and oxidized by reason of the spark or arc so as to interfere with the accurate operation thereof. To overcome this defect, we place a cooling device directly between the terminals T-T. This cooling device as shown consists of a thin, hollow, circular nozzle N which has 65 perforations 10 in its sides. This nozzle may be made out of any suitable non-oxidizing material, such as platinum, porcelain, etc. The nozzle is provided with an insulating joint 11, and is connected by a pipe 70 12 with a blower or fan F, so that in operation an air blast will be caused to flow directly against the active surfaces of the terminals and substantially parallel with the spark. This action will not tend to extinguish 75 the spark or arc and will keep the terminals cool and prevent the breaking down of the same. The action of the air blast is constant, as the air blast nozzle is permanently arranged between the terminals. 80

By the arrangements described the action of the spark or arc is not materially interfered with, and the terminals are kept cool and will last for a long time. The arrangements described may be also used in the 85 spark gap of a receiving plant or generally between any two terminals, the space between which forms a spark gap.

Other arrangements may be made for 90 practising the invention without departing from the scope thereof as expressed in the claims.

Having thus fully described our invention, what we claim and desire to secure by 95 Letters-Patent is:—

1. The combination of separated terminals forming a spark gap, and a cooling device arranged between said terminals consisting of a fixed nozzle arranged to direct 100 a blast parallel with the spark or arc.

2. The combination of separated terminals forming a spark gap, a fixed air blast nozzle arranged between the terminals and having openings for directing a blast of air 105 continuously on each terminal parallel with the spark or gap.

3. The combination of separated termi-

nals forming a spark gap, a hollow perforated blast nozzle arranged permanently between the terminals and having perforations for directing blasts on each terminal parallel with the spark or arc, and a source of air pressure connected thereto.

In testimony whereof we have hereunto

set our hands, in the presence of two subscribing witnesses.

WILLIAM E. D. STOKES, JR.
GEORGE W. DAVIS.
